UNITED STATES PATENT OFFICE.

LOUIS MAXWELL POTTS, OF BALTIMORE, MARYLAND, ASSIGNOR TO AUSTIN McLANAHAN, OF BALTIMORE, MARYLAND.

MEANS FOR SYNCHRONIZING TELEGRAPHIC AND OTHER APPARATUS.

1,201,621.

Specification of Letters Patent. Patented Oct. 17, 1916.

Application filed April 30, 1913. Serial No. 764,660.

To all whom it may concern:

Be it known that I, LOUIS MAXWELL POTTS, a citizen of the United States, residing in Baltimore city, and State of Maryland, have invented certain new and useful Improvements in Means for Synchronizing Telegraphic and other Apparatus, of which the following is a specification.

The primary object of this invention is to provide improved means for effecting and maintaining synchronous motion between moving parts located at a distance from each other, as for example, between transmitting and receiving apparatus in telegraph or other signaling systems where the same current which transmits the signals over the line also acts primarily to control the synchronism. In such systems as the Rowland, for example, this signaling and synchronizing current is subjected on the transmission of each signal to certain alterations or modification of its normal form, and when the number of modified impulses to the normal impulses exceeds a given amount, the regulating quality of the current becomes impaired and the synchronism less accurate. Take the case where the normal current on the line is an alternating current, and the signals formed by reversing the impulses in certain combinations, this will not materially affect the synchronism of apparatus primarily controlled by this current, in which the synchronism is regulated, for example, as described in U. S. Patent No. 726,750, as long as the proportion of the reversed impulses to the normal is less than fifty per cent., but this places a limitation on the number of signals which may be transmitted with a given signaling current. For example, suppose for each signal eight impulses are allotted. In such a case combinations of one, or two, or three impulses may be effected in each group of eight impulses to form the signals, but signals of combinations of four or more impulses cannot be formed without affecting the synchronism. Even when less than 50% are reversed there is a slight shift of the phase.

According to my present invention, the reversing or modifying of the impulses to form the signals does not affect the synchronism, so that combinations involving as many as seven impulses in a group of eight

may be modified without impairing the synchronism, and this is a great advantage, 55 since it permits of the utilization of a much greater number of the impulses for signaling. I accomplish this in one way by the improved means which I shall now describe in detail, reference being had to the accompanying drawings, wherein,

Figure 1, is a diagram of circuits in the apparatus embodying one form of my invention, and Fig. 2, a diagram illustrating the character of the synchronizing currents under various conditions.

Referring to the drawings, 1 and 2 indicate two direct current dynamos which constitute the source of the line signaling and synchronizing current. These dynamos are 70 so connected as to deliver positive current to conductor 3, and negative current to conductor 4, while their other terminals are connected to earth by a common conductor 5. Tapped on to the conductors 3 and 4, are a 75 series of pairs of stationary contacts 6 and 7, between each pair of which is adapted to move a contact 8. Each of the contacts 8 is connected to a separate segment of a transmitting commutator or sunflower 9, over which travels a brush 10, driven in any suitable way by direct current motor 11, receiving its current from local supply mains 12 and 13. Current is transmitted to line 14, from commutator 9, through a collector ring 80 15, over which travels brush 16, permanently electrically connected to brush 10, and also driven by motor 11. The movable contacts 8 normally rest against corresponding contacts 7, but these contacts are connected, as shown, alternately to opposite poles of the dynamos 1 and 2, as are also the contacts 6, so that as long as movable contacts 8 are all in engagement with contacts 7, impulses 85 of alternate polarity will be transmitted to 90 line through the commutator 9, as the brush 10 sweeps over successive segments of this commutator, which current will take the form indicated by the current diagram A, B, Fig. 2. The regular signals are formed 100 in this case by sending eight of the movable contacts 8 into engagement with stationary contacts 6 in various combinations, whereby the normal line current is reversed in corresponding combinations. The ninth contact 105 does not enter into the regular signal combi-

nations. This contact is for the purpose of operating a lamp, bell or other signal at the receiving station. Nothing new, however, is herein claimed for this system of transmission. It is merely shown as a part of a system in which my invention may be used. So far as the rest of the apparatus, shown at the transmitting end of the line is concerned, we may disregard this for the present. As for the operation of contacts 8, this may be effected by any suitable transmitting mechanism. Current from the transmitting sunflower 9-15 is transmitted over line 14 to a corresponding sunflower 15 device at a receiving station, the latter device comprising a collector ring 17, permanently connected to line, a commutator 18 having a number of insulated segments corresponding to those of a transmitting sunflower, and two electrically connected brushes 19 and 20, adapted to sweep over the commutator 18 and collector ring 17, respectively, and both driven by a direct current motor 21. The segments of commutator 18 are connected respectively through the coils of nine receiving relays 22, to a common conductor 23, in series with the coils of a synchronizing polarized relay 24, and the earth, as shown. Eight of these relays are for the regular signals, while the ninth is for the purpose of operating the lamp, bell or other extra signaling device referred to in connection with contacts 8. This much of the apparatus is in itself also old.

The motor 21 drives the brush 19 in synchronism with the brush 10, so that the successive relays 22 receive the impulses transmitted to line through the successive contacts 8. So long as these impulses are in the normal direction, these relays will not be affected; that is to say, their tongues will all remain against the back stop contacts, but whenever a reversed impulse traverses one of these relays, its tongue will be sent against its forward contact. Therefore, the relays 22 are operated in combinations depending upon the combinations of contacts 8 operated. These relays 22 may, therefore, be employed to operate printing or other receiving apparatus, but such mechanism forms no part of my present invention, nor is a description thereof necessary to an understanding of said invention.

While each relay 22 receives only those impulses distributed to it by the commutator 9, the relay 24 receives every line impulse, and acts primarily to regulate the synchronism of the motor 21 in the following way: One of the brushes of this motor is connected by conductor 25, to collector ring 26, associated with a synchronizing commutator 27, made up of a plurality of segments double in number those of the receiving commutator 18. The collector ring 26, and commutator 27, are swept by electrically connected

brushes 28 and 29, driven by the motor 21. Alternate segments of the commutator 27 are connected respectively to two conductors 30 and 31, which are in turn electrically connected to two stationary contacts 32 and 33, 70 adapted to be engaged alternately by a vibrating reed 34, made fast at one end to a suitable support 35, and carrying at its other end an armature 36, which moves in front of a magnet 37. I preferably provide the reed 75 with a stationary stop 33^a so that when the magnet 37 becomes deenergized the reed always starts from exactly the same phase position, the contacts 32 and 33 being in practice yielding to make certain contact. 80 The reed 34 is in permanent electrical connection through support 35 and conductor 35^a with the negative supply main 39.

Connected in circuit between wire joint 38, of conductor 25, and the negative main of 85 the local supply mains 39 and 40, is a resistance 41, which acts in conjunction with the vibrating reed 34 and commutator 27, to regulate the speed of the motor 21, as will now be described.

For the present purpose, we may regard the reed 34 as any body making contact alternately with contacts 32 and 33, at a rate bearing a fixed relation to the period of the line current. Then, if the reed 34 is 90 against either of its contacts 32, 33 while brush 28 is passing over any of the segments of the commutator 27 connected to the contact with which the reed is at that time engaging, it will be seen that the resistance 100 41 will be short circuited; while if the reed is engaging either of the said contacts at the same time that the brush 28 is passing over any of the segments of commutator 27 connected to the opposite reed contact; that is, the one which the reed is not at that time engaging, the resistance 41 will be in series 105 with the armature of motor 21. In one case the motor will receive much greater current than in the other.

Consider any case in which the vibrations of the reed and rotation of the brush arm have some phase relation between the above two. If any relation between the first two mentioned is continuously maintained, it 115 will be readily seen that at rapidly recurring intervals the resistance 41 will be in circuit and out of circuit with the motor 21. Depending upon the relation between the vibration of the reed and the rotation of 120 the brush 28, the intervals during which this resistance 41 is in circuit and out of circuit with the motor armature will vary in length and in addition to the regular current flowing through the armature, there will be a 125 pulsating current flowing through the same, and the strength of these impulses will depend upon the relation existing between the vibrations of the reed 34 and the rotation of brush 28. Consequently, while the reed 130

is vibrating in unison with the rotation of the brush, there can be various amounts of current flowing through the armature of the motor, depending upon the relation of the 5 reed and the brush 28.

If the rate of vibration of the relay tongue increases, the relation between the vibration of the reed and the rotation of the brush will change, but in such a manner as to 10 strengthen the impulses flowing through the motor armature; and consequently the speed of the motor will be increased, but only until this speed corresponds to the rate of vibration of the reed. If the armature of the 15 motor attempts to go faster than the vibrations of the reed, the impulses through the armature are weakened and the speed is kept normal. If the motor attempts to go slower, the impulses are strengthened, and 20 the speed of the motor is still kept normal. Consequently, the speed of the motor follows any changes in the vibrations of the reed, and any tendency for the motor to change its speed, as, for instance, a change in the 25 voltage in the power circuit, is immediately compensated for by a slight shift in the phase difference above mentioned.

The motor may be provided with a damper 21^a of the kind shown and described in 30 U. S. patent to Henry A. Rowland, No. 713,497, or other suitable means for steady- 35 ing its motion or reducing pumping. Such damper, in the case shown, comprises a closed casing mounted fast in the motor shaft and containing mercury or other suitable damping liquid.

The method of regulating the speed of motor 21, above described, barring the reed 34 and damper 21^a, is substantially the same 40 as that set forth in U. S. Patent No. 726,750.

If the reed 34 were replaced by relay 24; that is, if we substitute for the blade of the 45 reed, the tongue of the relay 24, in which event the segments in commutator 27 would correspond in number to those of commutator 18, the resultant effect on the motor 21 would be substantially the same as long as the line current continues to reverse regularly; that is, as long as no signals are transmitted 50 which modify the normal line impulses received by the relay 24, and even when these do not amount to fifty per cent. of the impulses transmitted, the synchronism is not appreciably affected, but when this 55 amount is exceeded, the regularity of the vibration of the tongue of relay 24 would become affected to such an extent as to interfere with the regulation of the motor. This is overcome in the present case by the 60 reed 34 and associated parts which will now be described in greater detail.

One of the coil terminals of the reed magnet 37 is permanently connected by conductor 42 to the tongue of relay 24, while the 65 other of said terminals is connected by con-

ductor 43 intermediate of two condensers 44 and 45, bridged across two conductors 46 and 47, from the supply mains 39 and 40, and these conductors are connected respectively through resistances 48 and 49 to the 70 tongue contacts 24^a and 24^b of the polarized relay 24.

The natural period of the reed 34 is twice that of the line current and for this reason 75 there are twice as many segments in commutator 27 as in commutator 18.

First assume the case when the dynamos are delivering to line an alternating current without signals being transmitted. The tongue of polar relay 24 will then vibrate 80 uninterruptedly between its contacts in unison with the impulses of this current. When its tongue is against contact 24^a, condenser 44 discharges and condenser 45 charges, sending an impulse to the magnet of the 85 reed 34, and when the tongue of relay 24 is against contact 24^b, condenser 44 charges and condenser 45 discharges, thus sending another impulse through the coils of magnet 37. Therefore, on each reversal of the line 90 current the reed magnet 37 receives an operating impulse. These impulses are indicated by the series C—D, Fig. 2. Each succeeding impulse is of different polarity, since one represents the charged current and the 95 other the discharge current of a condenser.

It is a well known principle in the theory of sound that if any body having a fixed natural period of vibration be acted upon by a periodic force varying slightly from 100 its natural period, that such body will vibrate in synchronism with the applied force. The reed 34 will therefore vibrate in synchronism with the regular alternations of the line current by virtue of the regulating force 105 constituting the impulses which pass through its magnet coils.

Now suppose a signal is transmitted, which we will assume is effected by reversing the direction of the third impulse from the left 110 in the series A—B, Fig. 2. The current will then be as indicated by the diagram E—F, Fig. 2. When this takes place the tongue of polar relay 24 will remain against the contact to which it was driven by the next 115 preceding impulse until an impulse comes along of reverse polarity. In other words, it will remain against said contact for the period of three impulses. During this time the reed magnet 37 receives but one impulse, 120 the second one on the left of the series G—H, Fig. 2, the two succeeding impulses shown in dotted lines being omitted owing to the non-reversal of the line current at that time. The reed 34 will not, however, be affected by 125 the temporary absence of the regulating impulses, but will continue its vibration at its own natural period, except that each vibration decreases in amplitude slightly due to the damping action of the air and the con- 130

tacts operated by the reed. The next succeeding line reversal will give it another impulse, and start it at its original amplitude and also correct its phase by the amount 5 it has gotten out. It is only necessary that the line reversals come sufficiently often, so that the reed does not get out of phase too much for the impulse to correct it. The maximum difference possible without loss of 10 synchronism is actually between 90° and 180°.

A weight 36 on the end of the reed 34 acts to keep up the amplitude of the reed longer when magnet coil 37 is receiving no im- 15 pulses.

The interval between the succeeding re- 20 versals of the line current, even when a great many are omitted, is short in comparison to the natural period of the rotating elements 25 of the distributing commutators driven by motors 21 on account of the steady action of the mercury damper 21^a and the heavy armature of the motor. The distributors therefore do not follow these slight changes 30 of phase of the reed when impulses are modified, but remains substantially the same independent of such phase changes at short intervals, so that the synchronism of the commutator brush 19 is almost absolutely 35 dead beat and retains a fixed phase relation.

Inasmuch as magnet 37 receives one impulse on each reversal of the line current, and since these impulses should act on the magnet only in one phase of the movement 40 of the reed, approximately in the out position, for example, the reed in the case shown must vibrate at twice the period of the line current. If the magnet 37 received these impulses at the out position, as well as the 45 in position of the reed, this would kill the effect of the magnet. The reed is, however, started into vibration by the reversal of the line current.

The period of the line current depends 50 upon the speed of motor 11, and in cases where the voltage of the driving current of this motor does not fluctuate materially, it will not be necessary to provide this motor with any extraneous speed governing means; 55 but when the motor is supplied with current from a commercial circuit, it will be advisable to provide such regulating means, in which event, I preferably employ an arrangement similar to that for governing the motor 21, barring the relay 24 and associated parts.

In the case shown the apparatus for governing the speed of motor 11 comprises a vibrating reed 50, magnet 51, contacts 52, 53 60 and 54, a synchronizing commutator 55, collector ring 56, and brushes 57 and 58 driven by motor 11, and a synchronizing resistance 59, all said parts being duplicates of corresponding parts at the receiving end of the 65 line and operating in the same way except

that the magnet of reed 50 is subject to impulses through contact 54. The resistance 60 is merely for regulating the current through magnet 51. The reeds 34 and 50 have precisely the same natural period. 70

The motors 11 and 21 may be provided with rheostats 61 and 62, but these are not essential, especially when the motors are de- 75 signed to run at the same speed for a given voltage.

While I have herein shown and described but one specific embodiment of my said invention, it should be understood that I do not limit the scope of my invention to such specific disclosure. The tuning fork or 80 reed, for example, may be replaced by some other element having a fixed natural period of motion, and various other changes effected without departing from the true spirit of 85 my invention.

What I claim is:—

1. The combination with an electric circuit including means to impress thereon electrical impulses alternating in polarity, of an element having a fixed natural period of 90 motion, and means controlled by the reversals of the current in said circuit to force the movement of said element.

2. The combination with an electric circuit including means to impress electrical 95 impulses thereon alternating in polarity, of an element having a fixed natural period of motion, and means controlled by the reversals of the current in said circuit to impart forced oscillations to said element after the 100 same has started into motion.

3. The combination with an electric circuit including means to impress thereon electrical impulses alternating in polarity, of an element having a fixed natural period of 105 motion, and means controlled by the reversals of the current in said circuit to give impulses to said element to maintain its periodic motion and also to bring its motion into phase with the reversals of said current. 110

4. The combination with an electric circuit including means to impress thereon electrical impulses alternating in polarity, of an element having a fixed natural period of motion, and means controlled by the reversals of the current in said circuit to start said element in motion and impart forced vibrations thereto to maintain its motion in phase with the reversal in polarity of said 115 impulses.

5. The combination with an electric circuit including means to impress thereon electrical impulses alternating in polarity, of an element having a fixed natural period of motion, a polarized relay controlled by 120 the reversals of the current in said circuit, a magnet adapted to give impulses to said element to maintain its periodic motion and also to bring its motion into phase with the 125 reversals of said current, and means con- 130

- trolled by said relay to impart an energizing current to said magnet on each reversal of the current in said circuit.
6. The combination with an electric circuit including means to impress thereon electrical impulses alternating in polarity, of an element having a fixed natural period of motion, a polarized relay controlled by the reversals of the current in said circuit, 10 a magnet adapted to force the motion of said element, and means comprising condensers and a source of current controlled by said polar relay to impart an energizing impulse to said magnet on each reversal of 15 the current in said circuit.
7. The combination with an electric circuit including means to impress electrical impulses thereon alternating in polarity, of a tuning fork or reed, and means controlled 20 by the reversals of the current in said circuit to impart forced oscillations to said reed after the same has started into motion.
8. The combination with an electric circuit including means to impress thereon 25 electrical impulses alternating in polarity, of a tuning fork or reed, and means controlled by the reversals of the current in said circuit to give impulses to said reed to maintain its periodic motion and also to 30 bring its motion into phase with the reversals of said current.
9. The combination with an electric circuit including means to impress electrical impulses thereon, of a member having a fixed natural period of motion, 35 means controlled by said impulses to synchronize said member, selecting means, a sunflower device distributing said impulses to said selecting means, and means controlled by said member to synchronize said sunflower device.
10. The combination with an electric circuit including means to impress electrical impulses thereon, of a tuning fork or reed, means controlled by said impulses 45 to synchronize said reed, selecting means, a sunflower device distributing said impulses to said selecting means, and means controlled by said reed to synchronize said sunflower device.
11. The combination with an electric circuit including means to impress electrical impulses thereon alternating in polarity, of means to modify said impulses to form signals, a sunflower device to distribute said impulses, a member having a fixed natural 55 period of motion, means to synchronize said sunflower device to said member, and means controlled by said impulses to synchronize 60 said member to said impulses.
12. The combination with an electric circuit including means to impress electrical signaling impulses thereon, of a tuning fork or vibrating reed, means controlled by the said impulses to set up forced vibrations in 65 said reed, a rotary sunflower device distributing said impulses to the means controlled thereby, and means controlled by said reed to regulate the speed of said sunflower device. 70
13. The combination with an electric circuit including means to impress thereon electrical impulses alternating in polarity, means to omit the normal reversal of one or more of said impulses in combinations 75 to form the signals, of an element having a fixed natural period of motion, and means controlled by the reversals of the current in said circuit to force the movement of said element, the said element continuing its motion naturally and freely during such periods of no reversal of the impulses. 80
14. The combination with an electric circuit, including means to impress electrical impulses thereon, alternating in polarity, 85 of a member having a fixed period of natural motion such that said member shall invariably be in substantially the same phase position at succeeding reversals of the current, and means to synchronize said 90 member with said impulses.
15. The combination with an electric circuit including means to impress electrical impulses thereon, of an element having a fixed natural period of motion, a relay controlled by said impulses, means controlled by said relay to generate electrical impulses the duration of which is independent of that 95 of the first mentioned impulses, and means controlled by said generated impulses to 100 control the phase of said element with respect to the phase of the first mentioned impulses.
16. The combination with an electric circuit, including means to impress electrical 105 impulses thereon alternating in polarity, of a member having a fixed period of natural motion such that said member shall invariably be in substantially the same phase position at succeeding reversals of the current, means to generate electrical impulses from said reversals, and means operated by said generated impulses to synchronize said 110 member with said first mentioned impulses.
- In testimony whereof I affix my signature 115 in presence of two witnesses.
